JOSEPH GOULBOURN AND WILFRID THOMAS MINETT, OF LEICESTER, ENGLAND,
ASSIGNORS TO UNITED SHOE MACHINERY CORPORATION, OF PATERSON, NEW
JERSEY, A CORPORATION OF NEW JERSEY.

PULLING-OVER MACHINE.

Application filed March 13, 1922. Serial No. 543,369.

To all whom it may concern:

Be it known that we, JOSEPH GOULBOURN and WILFRID T. MINETT, subjects of the King of England, residing at Leicester, Leicestershire, England, have invented certain Improvements in Pulling-Over Machines, of which the following description, in connection with the accompanying drawings, is a specification.

10 This invention relates to pulling-over machines including in their organization upper pulling and upper fastening means, and has for an object to aid in insuring a proper relation between the upper and the sole or insole in the upper fastening operation.

Pulling-over machines as commonly constructed comprise in their organization means for gripping and pulling the upper, means for laying or wiping the margin of the upper inwardly over the sole or insole (hereinafter termed for convenience the "sole") and for fastening the upper to the sole, and means for causing an inward movement of the upper gripping means to draw the upper over the edge of the sole before said gripping means releases the upper. In such an organization it may happen that there is not sufficient clearance between the upper gripping means and the margin of the sole in the overdrawing operation, as a result of which the margin of the sole may be displaced or the overlaying and fastening means may fail to assume effective control of the upper before the upper is released by the gripping means. If the upper fastening operation is performed under these conditions the upper is likely to be improperly or inadequately fastened. A reason for such lack of clearance may be that in the upper pulling operation the upper gripping means and the last did not assume the proper relation for effective clearance, or that the margin of the sole is not properly positioned close to the bottom face of the last.

Abnormal conditions such as above mentioned are usually encountered, if at all, at the toe end of the shoe, and in a well-known type of machine which comes automatically to a stop after the upper has been pulled and prior to the fastening operation it is a common practice of operators, if observa-

tion seems to require it, to impart a further pulling movement manually to the toe gripper, or to release the gripper and engage it with the upper nearer the margin of the latter, before again starting the machine. In operating on some kinds of work the operator will also usually press with his fingers upon the toe end of the sole to insure that its margin is properly positioned on the bottom of the last. Whether the conditions are proper for the operation of the fastening means thus depends largely upon the care or judgment of the operator, with the result that sometimes an upper is improperly fastened and the work has to be done over again. Furthermore, while in the majority of cases such corrective procedure on the part of the operator is unnecessary, a careful operator tends to develop the habit of imparting in every instance a corrective movement to the toe gripper, and it may be also of feeling of the toe of the sole, which diverts the operator's attention undesirably from other work. It is accordingly a further object of this invention not only to afford better insurance than heretofore that the upper fastening operation shall be properly performed, but also to save the operator's time and to relieve him of unnecessary labor.

To the above and other ends, a feature of the invention consists in a novel organization designed to afford the operator a reliable indication whether conditions at the end of the upper pulling operation are such that the upper fastening operation will be satisfactorily performed. For the purposes in view the invention, in its illustrative embodiment, provides a device which automatically signals the operator in case it is necessary for him to manipulate the upper gripping means in order to insure its proper clearance from the edge of the sole. In the construction shown the signal device comprises an electric lamp which is lighted automatically when the toe gripper has moved far enough to insure proper clearance and thus by failure to light indicates to the operator when manipulation of the gripper is required. Combined with the signal device in the illustrative machine, and as a further feature of the invention, there is provided holdown means for the sole which

- relieves the operator of any concern as to whether the margin of the sole is properly positioned close to the bottom face of the last and is a useful adjunct to the signal device in operating on work where the sole is insecurely fastened to the last or may tend for any other reason to lie at its margin in spaced relation to the bottom of the last.
- 10 The above and other features of the invention, including also novel features of the hold-down mechanism and various details of construction and combinations of parts, will now be more particularly described by reference to the accompanying drawing and pointed out in the claims.

20 The drawing is a view partly in side elevation and partly in section, showing the toe gripper and associated parts of a pulling-over machine in their relation to structure embodying the features of the present invention. The invention is illustrated, by way of example, in its application to a type of machine the general organization of which is shown and described in various prior Letters Patent of the United States including Patent No. 1,029,387, granted on June 11, 1912 upon an application of R. F. McFeely, and accordingly only such parts 25 of the machine as it is necessary to refer to for an understanding of the present invention are herein shown and described in detail.

30 It will be understood that the machine 35 comprises grippers for engaging the upper at the toe end and at opposite sides of the forepart, together with means which is automatically operative upon the starting of the machine to impart to the grippers yieldingly 40 through updraw springs a pulling movement heightwise of the last, the extent of such movement of the grippers depending upon the force of the springs and the resistance of the upper. In the drawings the toe gripper only is shown, comprising a gripper casting 2 and gripper jaws 4, the jaws being automatically closed on the upper in response to movement of the gripper operating means. The shoe is positioned relatively to the grippers by means of a sole rest 6 which in the upper pulling operation receives a slight downward rocking movement to depress the last within the upper. After the machine has come to a stop with the upper held under tension the operator may move the grippers manually in various well-known ways as observation of the work may show to be necessary. If the toe gripper, for example, needs to be moved farther in 50 the direction of the pull in order that it may properly clear the margin of the sole in the overdrawing operation or for any other reason, such movement may be imparted to the gripper by pushing upwardly on the front end of the gripper updraw lever 8. If con-

ditions render it desirable that the toe gripper engage the upper nearer the marginal edge of the upper, the operator, by use of the lever 8 and the usual gripper releasing hand lever 10, may relax the pressure of the gripper jaws upon the upper and re-engage the jaws with the upper nearer its edge. Thereafter the machine is started again for the overlaying and upper fastening operations which are performed by devices carried on front and side arms, the front arm 80 being shown at 12. As the front arm 12 moves rearwardly to wipe the margin of the upper over the sole and to position the fastening mechanism relatively to the edge of the shoe bottom, the toe gripper 2 is also 85 swung rearwardly by overdraw springs 13 to draw the upper inwardly over the edge of the sole, and before the front arm 12 completes its rearward movement it engages a finger 14 which serves to operate a gripper tripping latch 16 on the gripper whereby the gripper jaws 4 are caused to open and release the upper.

90 For the purposes of the present invention there is mounted on a bracket 18 on the frame of the machine an electric lamp 20 which is automatically lighted only when the toe gripper has moved far enough in the direction of the pull to position the jaws 4 in such relation to the plane of the last bottom that they will properly clear the edge 95 of the sole as the jaws are swung rearwardly to overdraw the upper. In circuit with the lamp 20 is an insulated contact member 22 on the bracket 18 and a co-operating contact member 24 comprising a plunger 100 yieldingly controlled by a spring 26 in a vulcanite block 28 on the sides of the toe gripper casing 2. When the plunger 24 makes contact with the member 22 in the upward movement of the toe gripper the circuit is closed and the lamp 20 is lighted. This indicates to the operator that the toe 105 gripper has moved far enough to insure proper clearance from the edge of the sole. If, on the other hand, the light should fail to appear, the operator is warned to impart a further movement to the toe gripper or to readjust the gripper jaws on the upper until the plunger 24 engages the member 22 and causes the lamp to be lighted. By means of a screw and slot connection 30 the block 28 with the plunger 24 may be adjusted lengthwise of the gripper casing to cause 110 the lamp to be lighted with the gripper jaws in different relations to the plane of the shoe bottom.

115 In order to assist in eliminating the need for manual movement of the toe gripper, the opposite toe gripper jaws 4 are provided respectively with pins 32 and 34 which are substantially perpendicular to the gripping faces of the respective jaws and the ends of 120 which are arranged to enter openings in the 130

jaws, these pins being arranged to prevent the jaws from gripping the upper too far from its marginal edge. The operator is thus assisted in presenting different uppers in the same relation to the toe gripper jaws, and as a result, if other conditions are favorable, the toe gripper will be moved automatically to such a point that it will properly clear the edge of the sole in the over-drawing operation.

To assist further in accomplishing the objects of the invention, the machine is provided with a holddown member 36 which is mounted in guideways on the rear face of the gripper casing 2 for sliding movement relatively to the gripper in directions substantially parallel to the direction of the pull. At its lower end the member 36 has a sole engaging foot 38 the lower face of which is curved lengthwise of the shoe so as to deflect the sole down under the foot if this end of the sole is spaced from the bottom of the last when the shoe is presented to the machine. By a screw and slot connection 40 the foot 38 is adjustable upwardly or downwardly. The hold-down member 36 is urged upwardly in its guideway by means of a spring 42 which is connected at its upper end to a pin 44 on the gripper casing and at its lower end to a hook 46 on the member 36. When the parts are in starting position, as illustrated in the drawing, the holddown member 36 is held by the spring 42 at its upper limit of movement determined by engagement of its upper end with the pin 44, and in this position the foot 38 is immediately behind the toe gripper jaws in position to engage the margin of the sole at the toe end and press the sole against the bottom of the last as the upper is presented between the open gripper jaws.

For controlling the holddown member 36 the upper portion 48 of the sole rest has a bore 50 extending lengthwise of the shoe and in generally parallel relation to the plane of the forepart of the shoe bottom and in this bore is slidably mounted a locking member or latch comprising a bar 52 which is drawn toward the toe gripper casing by a spring 54 connected at its opposite ends respectively to a hook 56 on the gripper casing and to a pin 58 which is fast on the bar 52 and slides in a slot 60 in the sole rest part 48 to prevent the bar 52 from turning. At its front end the bar 52 is provided with latching shoulders 62 which are arranged to engage shoulders 64 at the lower end of an opening in the holddown member 36 when the latter is in its depressed position, so that the bar 52 locks the holddown in operative position. When the toe gripper therefore receives its upper pulling movement the holddown 36 is maintained in its depressed position by the bar 52, and as the sole rest receives its downward rocking movement

the holddown is moved with it by the action of the bar, thus maintaining the toe end of the sole in close relation to the bottom of the last until the upper pulling operation has been completed.

In order that the holddown may not in any way interfere with the movement of the overlaying and fastening mechanism in its operation on the shoe, the machine is provided with means for effecting the release of the holddown member to permit its withdrawal by the spring 42. For this purpose the gripper tripping latch 16 is provided with a cam extension 66 which at the end of the updraw movement of the gripper is positioned to engage a surface 68 on the front end of the bar 52. When in the second stage of the cycle the front arm 12 by its action on the latch 16 causes the gripper jaws to open, this latch by its movement thrusts the bar 52 rearwardly so that the bar frees the holddown member 36 and permits it to spring upwardly out of the way under the influence of the spring 42. When at the end of the cycle the parts are returned to starting position the holddown member 36 is moved downwardly with the toe gripper until the gripper arrives in its lowermost position, whereupon the front end of the bar 52 again enters the opening in the holddown member to lock the member in place.

It will be evident that through the provision of the holddown member the operator is relieved of any concern as to the location of the toe end of the sole relatively to the plane of the forepart of the last bottom, and as far as clearance between the toe gripper and the sole is concerned has only to consider the position of the toe gripper jaws at the end of their upper pulling movement. Moreover, the signal device provided relieves the operator of any uncertainty with respect to the position of the gripper jaws and therefore assists in avoiding such improper fastening of the upper as might be due to an error of judgment, while it also relieves the operator of much unnecessary work.

While the invention is herein illustrated by reference to McKay shoe manufacture, it will be understood that the invention is not limited in utility to the manufacture of any particular kind of shoe, and it will also be recognized that in many of its novel and useful aspects the invention is not limited to operations performed at the toe end of the shoe.

Having described the invention, what we claim as new and desire to secure by Letters Patent of the United States is:

1. In a machine of the class described, the combination with upper gripping means, and mechanism for effecting relative movement of said upper gripping means and a

last to pull an upper over the last, of a device automatically operative to signal the operator at a predetermined point in said relative movement of the upper gripping means and the last.

2. In a machine of the class described, the combination with upper gripping means, and means for effecting relative movement of said upper gripping means and a last to pull an upper in the direction of the height of the last and thereafter to draw the upper inwardly over a sole on the bottom of the last, of a device controlled by said relative movement of the upper gripping means and the last in the direction of the height of the last for signaling the operator at a point in said relative movement when the upper gripping means is in position to clear the margin of the sole in the subsequent over-drawing of the upper.

3. In a machine of the class described, the combination with a gripper and means for operating it to pull an upper over a last, of a signal device controlled by the pulling movement of said gripper for indicating to the operator when the gripper has arrived at a predetermined point in said movement.

4. In a machine of the class described, the combination with a gripper and means for operating it to pull an upper over a last in the direction of the height of the last and thereafter to draw the margin of the upper inwardly over a sole on the bottom of the last, of a device automatically operative to indicate to the operator when the gripper has arrived at such a point in its movement heightwise of the last as to clear the margin of the sole in its subsequent over-drawing movement.

5. In a machine of the class described, the combination with upper gripping means automatically operative to pull an upper over a last and to come to a stop with the upper held 'under' tension and movable subsequently to draw the upper inwardly over a sole on the bottom of the last, and means for effecting a manual movement of said upper gripping means in the direction of the pull after said means has come to a stop, of a signal device controlled by the pulling movement of said upper gripping means for indicating to the operator when the manual movement of said gripping means is required to avoid interference with the margin of the sole in the over-drawing of the upper.

6. In a machine of the class described, the combination with a toe gripper and means for operating it to pull an upper over a last and thereafter to draw the upper inwardly over a sole on the bottom of the last, said gripper being manually adjustable heightwise of the last between the upper pulling and the over-drawing operations, of a device automatically operative to indicate to the operator whether manual adjustment of

said gripper is required to avoid interference with the margin of the sole in the over-drawing of the upper.

7. In a machine of the class described, the combination with a toe gripper movable to pull an upper over a last in the direction of the height of the last and thereafter to draw the margin of the upper inwardly over a sole on the bottom of the last, of an electrical device controlled by the movement of said gripper heightwise of the last for signaling the operator when the gripper has arrived at such a point in said movement as to clear the margin of the sole in its subsequent over-drawing movement.

8. In a machine of the class described, the combination with a gripper movable to pull an upper over a last, of an electrical signal device for indicating to the operator when the gripper has arrived at a predetermined point in its upper pulling movement, said device comprising co-operating contact members one of which is movable with the gripper into engagement with the other to close the circuit at said predetermined point in the movement of the gripper.

9. In a machine of the class described, the combination with a gripper and means for operating it to pull an upper over a last in the direction of the height of the last, of an electric lamp and circuit closing connections therefor comprising co-operating contact members one of which is carried by the gripper for signaling the operator when said gripper has arrived at a predetermined point in its upper pulling movement.

10. In a machine of the class described, the combination with a gripper movable to pull an upper over a last, of an electrical signal device comprising circuit closing connections controlled by the pulling movement of the gripper for indicating to the operator when the gripper has arrived at a predetermined point in said movement, said connections being relatively adjustable to vary the point in the movement of the gripper when the signal is given.

11. In a machine of the class described, the combination with upper gripping means and operating mechanism for effecting relative movement of said upper gripping means and a last to pull an upper in the direction of the height of the last and thereafter to draw the margin of the upper inwardly over a sole on the bottom of the last, of means automatically operative to insure that the margin of the sole adjacent to the upper gripping means will be closely positioned on the bottom of the last, and a device for indicating to the operator at the end of the upper pulling operation whether the upper gripping means is in position to clear the margin of the sole in the over-drawing operation.

12. In a machine of the class described, the

- combination with upper gripping means and operating mechanism for effecting relative movement of said upper gripping means and a last to pull an upper in the direction of the height of the last and thereafter to draw the margin of the upper inwardly over a sole on the bottom of the last, of a device arranged to engage the margin of the sole adjacent to said upper gripping means to position 5 said margin close to the bottom of the last in the upper pulling operation, and a device automatically operative to signal the operator at a point in said relative pulling movement heightwise of the last when the 10 upper gripping means is in such relation to the plane of the sole as to clear the margin of the sole in the overdrawing operation.
13. In a machine of the class described, the combination with a gripper movable to pull 20 an upper over a last in the direction of the height of the last, of a member for engaging the margin of a sole on the bottom of the last adjacent to said gripper to position said margin close to the bottom face of the last 25 in the upper pulling operation, and a device automatically operative to signal the operator when the gripper has arrived at a predetermined point relatively to the margin of the sole thus positioned.
14. In a machine of the class described, the combination with a gripper movable to pull an upper over a last in the direction of the height of the last and thereafter to draw the margin of the upper inwardly over a sole on 30 the bottom of the last, of holddown means automatically operative to position the margin of the sole close to the bottom face of the last prior to the overdrawing operation, and means for indicating to the operator at the 35 end of the movement of the gripper heightwise of the last whether the gripper is in position to clear the margin of the sole in the overdrawing operation.
15. In a machine of the class described, the combination with a gripper movable to pull an upper over a last in the direction of the height of the last and thereafter to draw the margin of the upper inwardly over a sole on the bottom of the last, of a hold- 40 down member for engaging the margin of the sole adjacent to said gripper to position said margin in close relation to the bottom face of the last in the upper pulling operation, a device automatically operative to 45 signal the operator when the gripper has arrived at such a point in its movement heightwise of the last that it will clear the margin of the sole thus positioned when it 50 draws the upper over the sole, and mechanism automatically operative to withdraw 55 said holddown member from the sole.
16. In a machine of the class described, the combination with a toe gripper movable to pull an upper over a last and there- 60 after to draw the upper inwardly over a sole 65 on the bottom of the last, said gripper being manually adjustable heightwise of the last between its upper pulling and overdrawing movements, of a device automatically operative to position the margin of the toe 70 end of the sole close to the bottom of the last, and a signal device controlled by the pulling movement of said gripper for indicating to the operator whether manual adjustment of the gripper is required to avoid 75 interference with the margin of the sole in the overdrawing operation.
17. In a machine of the class described, the combination with a toe gripper movable to pull an upper over a last in the direction of the height of the last and movable thereafter to draw the upper inwardly over a sole on the bottom of the last, of a hold- 80 down member movably mounted on said gripper and arranged to engage the margin of the toe end of the sole to position said margin in close relation to the bottom face of the last in the upper pulling operation, a signal device controlled by the toe gripper 85 for indicating to the operator when said gripper has arrived at such a point in its movement heightwise of the last as to clear the margin of the sole thus positioned in its subsequent overdrawing movement, and mechanism automatically operative to withdraw 90 said holddown member from its operative position.
18. In a machine of the class described, the combination with a gripper for pulling an upper over a last, and upper fastening 95 means movable inwardly toward the last, of a holddown member movably mounted on said gripper and arranged to engage the margin of the sole to position said margin upon the bottom of the last in the upper 100 pulling operation, and mechanism controlled by the inward movement of said upper fastening means for withdrawing said hold- 105 down member from operative position.
19. In a machine of the class described, the combination with a gripper for pulling an upper over a last, and upper fastening means movable inwardly toward the last, of a holddown member movably mounted on said gripper, a latch mounted independently 110 of said gripper for maintaining said hold- 115 down member in position to engage the margin of a sole on the bottom of the last in the upper pulling operation, spring means for withdrawing said holddown member from the margin of the sole, and mechanism for operating said latch by the inward movement of the upper fastening means to release the holddown member and permit it to 120 be withdrawn.
20. In a machine of the class described, the combination with a gripper comprising upper gripping jaws for pulling an upper over a last, and a tripping device on said gripper for causing the jaws to release the 125 130

upper, of a holddown member for engaging the margin of a sole on the bottom of the last to position said margin upon the bottom face of the last in the upper pulling operation, and mechanism controlled by said tripping device for withdrawing said holddown member from its operative position.

21. In a machine of the class described, the combination with a gripper comprising 10 upper gripping jaws for pulling an upper over a last, and a tripping device on said gripper for causing the jaws to release the upper, of a holddown member movably mounted on said gripper, a latch for maintaining said holddown member in position 15 to engage the margin of a sole on the bottom of the last in the upper pulling operation, spring means for withdrawing said holddown member from operative position, and 20 a device responsive to the operative movement of said tripping device for operating said latch to release the holddown member.

22. In a machine of the class described, the combination with a toe gripper for pulling 25 an upper over a last, of a holddown member movably mounted on said gripper, a locking member mounted independently of said gripper for movement lengthwise of the last and arranged to maintain said holddown member in position for engagement 30 with the margin of the toe end of the sole in the upper pulling operation, spring means for withdrawing said holddown member from operative position, and means for 35 moving said locking member rearwardly to release the holddown member.

23. In a machine of the class described, the combination with a toe gripper for pulling an upper over a last and a shoe bottom 40 rest for engaging a sole on the bottom of the last, of a holddown member movably mounted on said toe gripper, a member movably mounted on said shoe bottom rest and arranged to lock said holddown member in 45 position for engagement with the toe end of the sole in the upper pulling operation, spring means for withdrawing said holddown member from operative position, and means for imparting movement to said locking member to cause it to release said holddown member.

24. In a machine of the class described, the combination with a toe gripper for pulling an upper over a last, a tripping device on said gripper to cause it to release the 55 upper after the upper pulling operation, and a shoe bottom rest for positioning a shoe relatively to said gripper, of a holddown member movably mounted on said gripper, a member movably mounted on said shoe bottom rest for locking said holddown member in position to engage the margin of a sole on the last in the upper pulling operation, 60 spring means for retracting said holddown member, and mechanism operated by said tripping device for imparting to said locking member movement to release the holddown member.

25. In a machine of the class described, the combination with a toe gripper for pulling an upper over a last, and overlaying and fastening means for the upper, of a holddown member movably mounted on said gripper, a locking member mounted independently of said toe gripper for movement lengthwise of the last and arranged to maintain said holddown member in position for engagement with the margin of the sole in the upper pulling operation, a spring 70 for urging said locking member forwardly 75 toward the gripper, spring means for withdrawing said holddown member from engagement with the sole, and mechanism controlled by said overlaying and fastening means for imparting rearward movement to 80 said locking member to cause it to release the holddown member.

26. In a machine of the class described, the combination with a toe gripper for pulling an upper over a last, of a holddown member 90 movably mounted on said gripper and having a sole engaging face curved lengthwise of the last and positioned to engage the margin of the toe end of the sole as the shoe is presented to the machine, and mechanism for withdrawing said holddown member from operative position after the upper has been pulled.

In testimony whereof we have signed our names to this specification.

JOSEPH GOULDBOURN.
WILFRID THOMAS MINETT.
